CLAIM

The ornamental design for a solar powered electronic display assembly, as shown and described.

DESCRIPTION

FIG. 1 is a front perspective view of a solar powered electronic display assembly, showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is the front perspective view of FIG. 1 with certain environmental structure removed; and,

FIG. 10 is the rear perspective view of FIG. 8 with certain environmental structure removed.

The broken lines shown represent environmental structure and form no part of the claimed design.

1 Claim, 10 Drawing Sheets
